UNITED STATES PATENT OFFICE

172,729

WATCH BAND OR SIMILAR ARTICLE

Kurt Speck, Palisades Park, N. J., assignor to
Jacques Kreisier Manufacturing Corporation,
North Bergen, N. J., a corporation of New
Jersey

Application October 26, 1953, Serial No. 27,327

Term of patent 7 years

(Cl. D45—4)

To all whom it may concern:

Be it known that I, Kurt Speck, a citizen of the United States of America, residing at Palisades Park, county of Bergen, and State of New Jersey, have invented a new, original, and ornamental Design for a Watch Band or Similar Article, of which the following is a specification, reference being had to the accompanying drawing, forming part thereof.

Fig. 1 is a top plan view of a watch band, showing my new design;

Fig. 2 is an edge view thereof; and

Fig. 3 is a cross-sectional view thereof taken

along the line 3—3 of Fig. 2 and drawn to a larger scale.

The broken line disclosure in Figs. 1 and 2, respectively, represents leather.

The dominant features of my design reside in those portions shown in full lines.

I claim:

The ornamental design for a watch band or similar article, substantially as shown and described.
